(57) **CLAIM**

The ornamental design for a ceiling fan blade, as shown and described.

DESCRIPTION

FIG. 1 is a perspective bottom rear right view of a ceiling fan blade design.

FIG. 2 is a perspective top tip right view of the novel blade of FIG. 1.

FIG. 3 is a bottom view of the novel blade of FIG. 1.

FIG. 4 is a top view of the novel blade of FIG. 1.

FIG. 5 is a right side view of the novel blade of FIG. 1.

FIG. 6 is a left side view of the novel blade of FIG. 1.

FIG. 7 is an enlarged tip end view of the novel blade of FIG. 1; and,

FIG. 8 is an enlarged rear end view of the novel blade of FIG. 1.

The broken line showing of the mounting holes is included for the purpose of illustrating environmental structure and forms no part of the claimed design.

1 Claim, 6 Drawing Sheets
